CLAIM

The ornamental design for a trocar, as shown and described.

DESCRIPTION

FIG. 1 is a front side top isometric view of a trocar in accordance with the new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a rear elevational view thereof; and,

FIG. 7 is a front elevational view thereof.

The broken lines shown in FIGS. 3 and 6 represent portions of the article which are not claimed. The broken lines form no part of the claimed design.

1 Claim, 7 Drawing Sheets(56)
